CLAIM

The ornamental design for a combination of tape with a pressure point device, as shown and as described.

DESCRIPTION

FIG. 1 is a back perspective view of the combination of tape with a pressure point device showing a first embodiment of my new design having a half-dome shaped pressure point device;

FIG. 2 is a back view thereof;

FIG. 3 is a front view thereof;

FIG. 4 is a bottom view thereof;

FIG. 5 is a top view thereof;

FIG. 6 is a right side view thereof;

FIG. 7 is a left side view thereof;

FIG. 8 is a back perspective view of the combination of tape with a pressure point device showing a second embodiment of my new design having a tapered triangle shaped pressure point device;

FIG. 9 is a back view thereof;

FIG. 10 is a front view thereof;

FIG. 11 is a bottom view thereof;

FIG. 12 is a top view thereof;

FIG. 13 is a right view thereof;

FIG. 14 is a left view thereof;

FIG. 15 is a back perspective view of the combination of tape with a pressure point device showing a third embodiment of my new design having a pointed triangle shaped pressure point device;

FIG. 16 is a back view thereof;

FIG. 17 is a front view thereof;

FIG. 18 is a bottom view thereof;

FIG. 19 is a top view thereof;

FIG. 20 is a right thereof;

FIG. 21 is a left view thereof; and,

FIG. 22 is a front view showing an exemplary use for the combination of tape with a pressure point device.

The broken lines included in the Figures above depict environmental structure that form no part of the claimed design. The cutaway symbols shown in broken lines in the
